Des. 224,206
Patented July 11, 1972

224,206

COMPARTMENTED TRAY

Steven J. Cyr and Mark W. Whelan, Chippewa Falls,
Wis., assignors to Standard Oil Company, Chicago, Ill.

Filed Aug. 28, 1970, Ser. No. 24,753

Term of patent 14 years

Int. Cl. D9—03

U.S. Cl. D9—185

F/G. 1

FIG. 2

FIG. 3

FIG. 4

FIG. 5

FIG. 6

FIG. 7

FIG. 1 is a perspective view of a compartmented tray.
FIG. 2 is a plan view of the interior of a compartmented tray.

FIG. 3 is a plan view of the exterior of a compartmented tray.

FIG. 4 is a front elevational view of a compartmented tray.

FIG. 5 is a rear elevational view of a compartmented tray.

FIG. 6 is a side elevational view of one end of a compartmented tray, the opposite end being the mirror image of FIG. 6.

FIG. 7 is a perspective view of a modified form of the design of FIGS. 1-6 wherein the raised portion on the front cavity divider has been removed so that the divider has an essentially planar upper surface.

We claim:

The ornamental design for a compartmented tray, as shown and described.
